(No Model.)

L. RIEDEL.
HAY RACK.

No. 414,824.

Patented Nov. 12, 1889.

UNITED STATES PATENT OFFICE.

LOUIS RIEDEL, OF BAKER, KANSAS.

HAY-RACK.

SPECIFICATION forming part of Letters Patent No. 414,824, dated November 12, 1889.

Application filed October 24, 1888. Serial No. 289,012. (No model.)

To all whom it may concern:

Be it known that I, LOUIS RIEDEL, a citizen of the United States, residing at Baker, in the county of Brown and State of Kansas, have invented a new and useful Improvement 5 in Hay-Racks, of which the following is a specification.

My invention relates to an improvement in hay-racks for wagons; and it consists in the 10 peculiar construction and combination of devices that will be more fully set forth hereinafter, and particularly pointed out in the claims.

The object of my invention is to provide a 15 wagon hay-rack which is made of detachable parts sufficiently light to be readily handled by one man, whereby the rack may be placed upon and taken from the wagon-bed of the wagon and put together and disassembled by 20 a single person, and whereby the rack when disassembled may be readily stored under a shed or barn within a comparatively small space to protect it from the elements.

In the accompanying drawings, Figure 1 is 25 a side elevation of a wagon-body and a hay-rack embodying my improvement placed on the said body. Fig. 2 is a top plan view of the same. Fig. 3 is a vertical transverse sectional view taken on the line xx of Fig. 2. Fig. 30 4 is a detailed perspective view of one of the blocks C' .

A represents the vertical side-boards of the wagon-bed, which are provided on their inner sides at their ends with vertical grooves B, 35 adapted to receive the ends of the end-boards C in the usual manner. Said end-boards are secured in place between the side-boards by screws or bolts b.

D represents U-shaped straps or keepers, 40 which are secured to the side-boards A at suitable distances apart and depend from the lower edges thereof, as shown, and in the said straps or keepers are fitted the ends of cross-bars E, which are arranged transversely under 45 the boards A.

F represents the bottom boards, which are arranged between the side-boards A, have their ends bearing against the inner sides of the end-boards C, and are supported on the 50 cross-bars E.

G represents a vertical standard, which comprises a pair of downwardly-diverging

bars H, having their upper ends rabbeted in the lower end of a vertical bar I and secured to the same by transverse bolts K. The upper end of the bar I has a vertical open slot L, which is adapted to receive the lines, and constitutes a line or rein holder or guide. The lower ends of the bars H are pivoted on the inner sides of the boards A, near the front 55 end of the wagon-bed, by means of transverse bolts M, and thereby the standard is hinged to the side-boards A, is adapted to be turned to a vertical position, and to be disposed in a horizontal position in the bottom of the wagon-bed. The said bars H are further provided on their outer side, near their lower ends, with eyes or keepers N, which are adapted to be engaged by hooks O, that are pivoted to the inner sides of boards A, and thereby the 60 standard may be secured in its vertical position.

On the upper edges of the boards A, at suitable distances apart, are secured plates P, the sides of which are vertical, and also secured to the inner sides of the boards A and arranged directly opposite the said plates P are inverted-U-shaped keepers or straps R, which project beyond the upper edges of the boards. The side wings S are each formed 80 of two transverse sections. Each section has a pair of cross-bars V, which have their inner ends pointed and adapted to be fitted in the loops or keepers R, and are provided on their under sides with irons W, which are adapted 85 to bear on the plates P, and have their inner ends bent downward vertically to form arms X, which bear against the inner sides of the boards A, and thereby prevent the bars V from slipping lengthwise out of the loops or 90 keepers R. The outer ends of the bars of one section are connected together by longitudinal boards Y, and the outer ends of the bars of the other sections are connected together by boards Z, which are arranged in the same 95 planes with the boards Y. On the upper sides of these boards Z are secured sector-shaped blocks A', on the peripheries of which are bolted transverse bars B', said sector-blocks and transverse bars constituting 100 guards to keep the hay off the rear wheels of the wagon, as will be readily understood.

On the front side of the foremost bar V of each rear wing-section is bolted a block C',

which has notches or recesses D' in its upper side at its ends that receive the rear ends of the boards Y and serve to support the rear ends of the same when the wing-sections are 5 in position on the wagon.

When the wing-sections are removed, the wagon-bed may be employed for hauling sand, stones, manure, and other articles, and when the wing-sections are secured in place on the 10 wagon-bed they constitute a rack adapted for hauling hay and fodder.

It will be understood from the foregoing description and by reference to the accompanying drawings that the wagon-bed and side 15 wings are made in separable parts, which are sufficiently light to be readily handled by one man, who is thus enabled to put the parts together and to disassemble the same without assistance—a convenience the utility of which 20 will be readily recognized by farmers.

Another advantage resulting from this construction of the rack is that the same when disassembled may be readily stored in a comparatively small space in a barn or under a 25 shed and protected from the elements when not in use.

Having thus described my invention, I claim—

1. The side racks or wings comprising the 30 detachable sections, each composed of the

cross-bars, and the longitudinal boards secured to said cross-bars, one section having on its front side the blocks C', provided with notches or recesses D' to receive the rear ends of the boards of the other section, sub- 35 stantially as described.

2. The combination of the wagon-bed having the plates P and keepers R on its sides, the plates on one side being arranged opposite the keepers on the other, and the side 40 racks comprising the detachable sections, each composed of the cross-bars V, and the longitudinal boards secured to said cross-bars, one section having the blocks C' on its front side provided with notches or recesses D' to receive the rear ends of the boards of the other section, the said side racks being secured in position on the bed by having their cross-bars V resting on the plates P on one side of the 45 wagon-bed and the inner ends of said cross-bars fitted in the keepers R on the other side, substantially as described.

In testimony that I claim the foregoing as my own I have hereto affixed my signature in presence of two witnesses.

LOUIS RIEDEL.

Witnesses:

F. E. ROGERS,
JAMES BOND.
